CLAIM

The ornamental design for a trekking pole tip cover, as shown and described.

DESCRIPTION

FIG. 1 is a bottom-rear perspective view of the trekking pole tip cover, showing my new design;

FIG. 2 is a front view of the design illustrated in FIG. 1; FIG. 3 is a rear view of the design illustrated in FIG. 1; FIG. 4 is a right side view of the design illustrated in FIG. 1;

FIG. 5 is a left side view of the design illustrated in FIG. 1; FIG. 6 is a top view of the design illustrated in FIG. 1; FIG. 7 is a bottom view of the design illustrated in FIG. 1; and,

FIG. 8 is a top-front perspective view of the design illustrated in FIG. 1.

The uneven-length broken lines immediately adjacent to the shaded areas define a bound of the claimed design and forms no part thereof. The even-length broken lines in the drawings are for the purpose of illustrating unclaimed portions of the trekking pole tip cover and a trekking pole, and form no part of the claimed design.
